UNITED STATES PATENT OFFICE.

GEORGE BESTER McKINNEY, OF BARRY, ILLINOIS.

STOOL.

SPECIFICATION forming part of Letters Patent No. 659,089, dated October 2, 1900.

Application filed February 3, 1900. Serial No. 3,835. (No model.)

To all whom it may concern:

Be it known that I, GEORGE BESTER Mc-
KINNEY, a citizen of the United States, and a
resident of Barry, in the county of Pike and
5 State of Illinois, have invented a new and
useful Improvement in Stools, of which the
following is a full, clear, and exact descrip-
tion.

My invention relates particularly to an im-
10 provement in the construction of dentists'
stools; and one purpose of the invention is
to so construct the stool that it will have a
yielding or spring action laterally in any di-
rection, the spring-section permitting said ac-
15 tion being a portion of the standard or up-
right of the stool.

It is a further purpose of the invention to
provide means whereby the seat of the stool
20 may be conveniently and expeditiously raised
and lowered and held firmly in adjusted po-
sition.

The invention consists in the novel con-
struction and combination of the several
parts, as will be hereinafter fully set forth,
25 and pointed out in the claims.

Reference is to be had to the accompanying
drawings, forming a part of this specification,
in which similar characters of reference indi-
cate corresponding parts in both figures.

30 Figure 1 is a perspective view of the im-
proved stool, and Fig. 2 is a longitudinal cen-
tral section through the stool.

The standard or upright A is tubular and
35 is provided with a coil-spring section B of
any desired length, which coil-spring section
B is attached to a suitable base C in any ap-
proved manner. As shown, the lower por-
tion of the coil B extends over and is at-
tached to a stud 10, extending upward of the
40 center of the base. The tubular or main
section A of the upright or standard of the
stool preferably enters the lower or spring
section B at its upper end, and the upper
portion of the spring-section of the standard
45 may be attached to the main section A, if
desired; but the main section A of the stand-
ard is provided, preferably, with an exterior
collar 11, which rests upon the spring-sec-
tion B.

50 The main section A of the standard of the
stool is provided upon its inner surface with
teeth 12, in the form of a screw, the teeth be-

ing inclined in an upward direction, as shown
in Fig. 2, and usually the entire inner surface
of the main section A of the stool-standard 55
is thus toothed or threaded. The seat D is
provided with a bottom chamber 13, as is
also best shown in Fig. 2, and a tubular stem
14 is screwed or otherwise fastened to the
bottom central portion of the seat D, which 60
stem 14 is held to slide freely within the main
portion A of the standard of the stool and
may extend within the spring-section B, if
desired. Where the tubular stem connects
with the seat of the stool a shoulder 15 is 65
preferably formed, which in the lower pos-
ition of the seat rests upon the upper end of
the main section A of the stool-standard.

Opposing longitudinal slots 16 are made in
the lower end portion of the tubular stem of 70
the seat D, and a latch 17 has horizontal
movement in the said tubular stem of the
seat, being adapted to extend within or out
through either of the slots 16, as shown in
Fig. 2. This latch is provided at one of its 75
side edges with teeth 18, adapted to fit the
teeth 12 in the main tubular section A of the
standard of the stool, and the said latch 17
is also provided in each side with an inclined
or diagonal slot 19, extending in direction of 80
its upper and lower edges. The latch is
manipulated through the medium of a rod 20,
the lower end 21 whereof is flattened and
passes through a slot made centrally and ver-
tically in the latch, and the said flattened 85
surface 21 of the rod 20 is provided with pins
22, which extend through the diagonal slots
19 in the latch. Thus when the rod 20 is
drawn upward the pins 22 are made to travel
upward also, and the toothed edge of the 90
latch is then carried out of engagement with
the teeth on the standard of the stool, and
the stem connected with the seat may be
raised or lowered, as desired.

The rod 20 may be manipulated in differ- 95
ent ways; but preferably it is controlled as
shown in Fig. 2, wherein a spring-arm 23 is
located in the chamber 13 in the bottom of
the seat of the stool, and one end 24 of this arm
is attached to the bottom portion of the stool,
while the other end extends out through an
opening 26, made also in the bottom of the
seat of the stool, and the outer end of the
arm 23 usually terminates in a button 25.

The rod 20 has a hinge connection with the central portion of the spring-arm 23.

It will be observed that owing to the coil-section in the standard of the stool the said standard may be inclined laterally in any direction that may be found advantageous to the occupant of the stool and that the stool may be quickly and conveniently adjusted as to height. Furthermore, the entire construction of the stool is not only durable, but simple, and the stool is in no manner rendered unsightly by the improvement.

Having thus described my invention, I claim as new and desire to secure by Letters 15 Patent—

1. A stool comprising a base having a stud extending upward therefrom, a seat, a standard having a laterally-yielding lower coil-spring section extending over the stud on the 20 base and a rigid upper section fitting within the coil-spring section, substantially as described.
2. A stool comprising a base, a standard mounted on the base and having a coil-spring section and a tubular rigid section fitting one 25 within the other and a seat provided with a post having sliding movement in the standard, substantially as described.
3. A stool comprising a base, a standard or 30 upright having a lower coil-spring section attached to the base, and an upper rigid tubular section adapted to enter the upper end of the coil-spring section, the said upper section being provided near its lower end with an external collar adapted to rest on the upper end 35 of the coil-spring section, and a seat provided with a stem fitting within the said standard, substantially as described.
4. In a stool, a base having a stud extending 40 upward therefrom, a standard comprising a tubular rigid section, and a coil-spring section extending over and attached to the said stud on the base, the tubular rigid section having interiorly-located teeth, a seat having a 45 chamber in its lower portion extending from side to side, a post for the seat having sliding movement in the standard, a latch having

teeth arranged for engagement with the teeth in the standard, an arm located in the chamber of the seat and secured at one end to the bottom of the seat, the other end of said arm extending out through an opening in the bottom of the seat and a rod connecting said arm with the said latch, substantially as described.

5. In a stool, a base, a standard comprising a tubular rigid section, and a coil-spring section, the tubular rigid section having interiorly-located teeth, a seat having a bottom chamber, a hollow post for the seat having sliding movement in the standard, the said post having opposing slots, a latch having horizontal movement in the said post and adapted to extend within the post or out through either of the slots, the said latch being provided at one of its side edges with teeth 60 adapted to fit the teeth of the standard, the said latch being also provided in each side with a diagonally-arranged slot extending in direction of its upper and lower edges, a rod having a flattened lower end extending 65 through a central vertical slot in the latch, the said flattened surface being provided with pins extending through the diagonal slots in the latch, a spring-arm located in the chamber in the bottom of the seat and secured at 70 one end to the seat, the other end of said arm extending out through an opening formed in the bottom of the seat, the upper end of the said rod having a hinge connection with the central portion of the spring-arm, for the 75 purpose set forth.

6. A stool comprising a base, a tubular standard having a laterally-yielding section mounted on said base, a rigid section, fitting within the laterally-yielding section, and a 80 seat provided with a post adjustably held in the said standard, substantially as described.

In testimony whereof I have signed my name to this specification in the presence of two subscribing witnesses.

GEORGE BESTER MCKINNEY.
